UNITED STATES PATENT OFFICE.

JOHN L. JUDGE, OF NEW YORK, N. Y.

BUILDING-BLOCK.

No. 858,988.

Specification of Letters Patent.

Patented July 2, 1907.

Application filed February 25, 1907. Serial No. 359,270.

To all whom it may concern:

Be it known that I, JOHN L. JUDGE, a citizen of the United States, residing in the city of New York, borough of Queens, county of Queens, and State of New York, have invented certain new and useful Improvements in Building-Blocks, of which the following is a specification.

The invention is designed to attain a simple structure of building block adapted to be conveniently and 10 economically manufactured by machine, and affording certain practical advantages in use. Thus provision is made for damming the mortar in such manner as to embed the horizontal bearing surfaces therein, thereby insuring a water tight seal at the horizontal joints, 15 while a like result is attained in so far as the transverse or vertical joints are concerned by the use of lap tiles fitting within the abutting ends of the adjoining blocks, substantially as hereinafter set forth.

The invention consists in the construction and arrangement of parts hereinafter described and claimed 20 specifically.

In the accompanying drawings, Figure 1, is an isometrical perspective of a portion of a wall viewed externally, illustrating the use of my improved blocks 25 and lap tiles; Fig. 2, is an isometrical view of one of my building blocks looking toward the outer surface thereof; Fig. 3, is an isometrical view of one of the lap tiles; Fig. 4, is a central vertical longitudinal section of a portion of the wall shown in Fig. 1; Fig. 5, is a 30 transverse section of the wall taken upon plane of line 5—5—Fig. 4; Fig. 6, is a transverse section of the wall taken upon plane of line 6—6—Fig. 4; Fig. 7, is an isometrical view of one of my building blocks, looking at the inner side thereof; Fig. 8, is an isometrical view 35 illustrating the use of my blocks and lap tiles as facing for brick work; Fig. 9, a transverse section of Fig. 8; Fig. 10, is an isometrical view partly in section, illustrating the use of my building blocks and lap tiles as a 40 facing for concrete or the like; Fig. 11, is a transverse section of Fig. 10; Fig. 12, a sectional view upon an enlarged scale illustrating the use of the dam shoulders.

The blocks B, of elongated rectangular form in general outline, are each formed with a plain outer side, 45 or "face" 1, and with the parallel surface 2, on the opposite or inner side of the block. A lateral recess 3 is formed in this inner side of the block extending from the surface 2 into the longitudinal groove 4.

The longitudinal groove 4 extends to and through 50 both ends 5, 5, of the block, and is preferably though not necessarily semi-circular as related to the cross section of the block B, and of such width as to create relatively narrow parallel bearing surfaces 6, 6, on either side of the groove 4. This longitudinal groove 55 4, is also by preference of greater depth than the lateral recess 3, for the purpose hereinafter set forth.

On the side 7 of the block B opposite to that in which the groove 4 is formed, are longitudinal parallel shoulders 8, 8, which bound the inner edges of the bearing surfaces 9, 9, which latter are relatively wider than 60 the bearing surfaces 6—6, on the opposite side of the block B. These longitudinal parallel shoulders 8, 8, perform a double function in that they not only act as dams to hold back the mortar (m, as illustrated in Fig. 12) against the narrower bearing edges 6, thereby positively and effectually sealing the joint between said narrower bearing surfaces 6 and the opposed wider bearing surfaces 9 on the adjoining block, but they also centralize and support laterally the lap tiles L, which are made of a thickness equal approximately 70 to the difference in width between the narrower bearing surfaces 6 and the wider bearing surfaces 9. In other words, the longitudinal dam shoulders 8, cause the narrower bearing surfaces 6 to be embedded in the mortar in such manner as to insure a water tight 75 seal, and they also lock the lap tiles L, and hence the blocks B, against lateral play or irregularity in position, thus insuring the perfect alinement of all the parts.

The lap tiles L conform in shape to, and fit within, 80 the groove 4 of the blocks, and are so placed that the abutting ends of adjoining blocks over-lap the tiles L, thereby closing the slight vertical spaces between the opposed ends of the tiles, and affording a perfectly tight lateral joint since the intervening mortar will 85 form, in cross section, an inverted T-shaped rectangular seal between the opposed surfaces of the ends of the blocks and the convex surfaces of the lap tiles, as will be readily understood by reference to Fig. 4, and as shown therein by way of illustration by the thickened lines at the joint marked a.

When my blocks are used as a facing for either brick work as shown in Figs. 8 and 9, or for concrete, as shown in Figs. 10 and 11, the lateral recess 3 is utilized in effecting an interlocking of the parts,—the union 95 being attained in the first case by extending the brick work into the blocks through the said lateral recesses 3, and in the second case by causing the concrete to protrude into the blocks through the said lateral openings 3. In the latter case the blocks B are preferably 100 reversed in position, with their grooved sides upward, as shown in Figs. 10 and 11, in which case the difference between the depth of the recesses 3 and the depth of the grooves 4 aids in the interlocking of the parts, since the portions of concrete within the channels, 105 when set, are locked therein by the edges of the recesses which thus constitute retaining shoulders, as will be readily understood by reference to Fig. 11.

Each block is preferably though not necessarily made with two or more longitudinal air spaces of oval 110 or other desired form in cross section of the block, said spaces 12, extending through the entire length of

the block from one end face 5 to the other face 5 for the purpose of facilitating drying and burning and to lighten the block.

It will thus be seen that my building blocks and 5 lap tiles, while simple in form and structure, are fully adapted to the various requirements and conditions of actual use, and also that perfect, water tight seals between joints are insured.

What I claim as my invention and desire to secure 10 by Letters Patent is,

1. The combination of a building block of the character designated, formed on one side with a groove extending through it from one end face to the other with parallel bearing surfaces on each side of said groove, said block 15 being formed on the opposite side with parallel bearing surfaces of greater width than those on the side of the block first mentioned, and with parallel dam shoulders bounding the inner edges of said broader bearing surfaces, and a lap tile fitting the groove in the block, said lap tile being of a thickness approximately equal (less the thickness of the mortar seal) to the difference in width between 20 said parallel bearing surfaces on the opposite sides of the block, for the purpose described.

2. The combination of a building block of the character 25 designated, formed on one side with a semi-circular groove extending through it from one end face to the other with parallel bearing surfaces on each side of said groove, said block being formed on the opposite side with parallel bearing surfaces of greater width than those on the side 30 of the block first mentioned and with parallel dam shoulders bounding the inner edges of said broader bearing surfaces, and a semi-circular lap tile fitting the semi-circular groove in the block, said semi-circular lap tile being of a thickness equal approximately (less the thickness of 35 the mortar seal) to the difference in width between the said parallel bearing surfaces on the opposite side of the block, for the purpose described.

3. A building block of the character designated, formed 40 on one side with a groove extending through it from one face to the other with parallel bearing surfaces on each side of the groove and with a lateral opening extending through the edge of one side wall of the groove, said block being also formed on the side opposite to that first mentioned with parallel bearing surfaces of greater width 45 than those first mentioned, with parallel dam shoulders bordering the inner edges of said broader bearing surfaces and a lap tile fitting the groove in the block, said lap tile being of a thickness approximately equal (less the thickness of the mortar seal) to the difference in width between 50 the parallel bearing surfaces on the said opposite sides of the block, for the purpose described.

4. A building block of the character designated, formed 55 on one side with a longitudinal groove extending through it from one end face to the other with parallel bearing surfaces on each side of said groove and with a lateral opening into said groove through one side wall of the block, said block being also formed on the side opposite

that first mentioned with parallel bearing surfaces of greater width than those on the said first mentioned side and with parallel dam shoulders bounding the inner edges 60 of said broader bearing surfaces, and a lap tile fitting the longitudinal groove in the block, said lap tile being of a thickness approximately equal (less the thickness of the mortar seal) to the difference in width between said parallel bearing surfaces on the opposite sides of the 65 block, for the purpose described.

5. A building block of the character designated, formed on one side with a groove extending through it from one face to the other with parallel bearing surfaces on each side of the groove and with a lateral opening of less depth 70 than said groove, extending through the edge of one side wall of the groove, said block being also formed on the side opposite to that first mentioned with parallel bearing surfaces of greater width than those first mentioned, with parallel dam shoulders bordering the inner edges of said 75 broader bearing surfaces, and a lap tile fitting the groove in the block, said lap tile being of a thickness approximately equal (less the thickness of the mortar seal) to the difference in width between the parallel bearing surfaces on the said opposite sides of the block, for the purpose described.

6. A building block of the character designated, formed on one side with a longitudinal semi-circular groove extending through it from one face to the other with parallel bearing surfaces on each side of the groove and with a lateral opening extending through the edge of one side wall of the groove, said block being also formed on the side opposite to that first mentioned with parallel bearing surfaces of greater width than those first mentioned, with parallel dam shoulders bordering the inner edges of 90 said broader bearing surfaces and a semi-circular lap tile fitting the said longitudinal semi-circular groove in the block, said lap tile being of a thickness approximately equal (less the thickness of the mortar seal) to the difference in width between the parallel bearing surfaces on 95 the said opposite sides of the block, for the purpose described.

7. A building block of the character designated formed on one side with a longitudinal semi-circular groove extending through it from one end face to the other with 100 parallel bearing surfaces on each side of said semi-circular groove, and with a lateral opening into said semi-circular groove through one side wall of the block, said block being also formed on the side opposite to that first mentioned with parallel bearing surfaces of greater width than those on 105 said first mentioned side, and with parallel dam shoulders bounding the inner edges of said broader bearing surfaces, in combination with a lap tile fitting said semi-circular groove in the block said lap tile being of a thickness approximately equal (less the thickness of the mortar seal) 110 to the difference in width between said parallel bearing surfaces on the said opposite sides of the block, for the purpose described.
